UNITED STATES PATENT OFFICE.

JOHN S. BAY, OF DENVER, COLORADO.

BRIDGE SIGNAL.

Application filed February 11, 1924. Serial No. 691,982.

To all whom it may concern:

Be it known that I, JOHN S. BAY, a citizen of the United States, residing at the city and county of Denver and State of Colorado, have invented certain new and useful Improvements in Bridge Signals; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to signals for railways and has special reference to a signal intended primarily for use in connection with railway bridges, to set a danger signal if the water in the stream should rise above 20 a certain level or if the bridge should be destroyed by fire.

In many parts of our country the railways cross streams of various sorts. Some of these are mere rivulets and even dry 25 ditches for the most part of the year, but in time of storm these very often become raging torrents. It has frequently happened that bridges have been washed away or so 30 badly damaged by floods that the train would fall through when it entered upon the bridge. As the bridges have not been provided with any special signalling means, the engineer has had no warning and in several 35 instances has driven the train onto the bridge, only to have it fall through and into the river bed.

Instances have also occurred in which 40 bridges have been destroyed by fire, leaving the rails suspended across the stream in such a manner that the block signal, which would 45 become operative if the rail had been broken, did not operate.

It is the object of this invention to produce a simple and inexpensive mechanism 50 that may be applied to any existing bridge and which shall be so constructed that it will cause a danger signal to be set whenever the water in the stream rises above a predetermined level and in case the bridge 55 is damaged by fire. My signal is so constructed that after it has been set into operation, it will be automatically disconnected from the bridge so that it will continue its 60 operation regardless of what happens to the bridge structure.

My invention, briefly described, consists

of a float supported by a suitable steel framework at a height corresponding to the danger level of the water. When the water rises above this level, it raises the float and this causes a switch to be closed, whereby a motor is set into operation and moves a signal arm to which red lights are attached. When the motor starts, it automatically disconnects the wires running to the bridge 65 and makes connections directly to the source of electrical energy. In case of fire the signal is set into operation by means of a thermal circuit closer.

My invention can be most clearly described and most readily understood when reference is had to the accompanying drawings in which the preferred embodiment thereof is illustrated, and in which:

Fig. 1 is a view showing a railroad bridge 75 with the signal posts on each side thereof;

Fig. 2 is a side elevation of a bridge and shows the manner in which the float-operated switch is supported and the manner in which the thermal circuit closers are attached to the bridge;

Fig. 3 is a vertical section of one of the thermal circuit closers;

Fig. 4 is a vertical section of one of the signal posts;

Fig. 5 is a view, to an enlarged scale, of a 85 circuit-changing mechanism; and

Fig. 6 is a detail showing the manner in which the current to the signal lights is intermittently broken.

Numeral 1 designates a bridge of any type which spans a stream, indicated by numeral 2. On each side of the stream I place a plurality of signal posts 3, 4 and 5. Of course a greater number may be used if desired and the number may be reduced to a single one, but in my opinion it is desirable to employ three signals in the manner shown. Signal posts 4 and 5 carry a single stationary red light only while signal post 3 carries 100 two red lights secured to the ends of the rotatable arm 6.

The signal post 3 is secured to the top of a housing 7 which encloses a motor 8 and a battery 9 which is preferably located in a 105 frost-proof pit 10. One end of the motor shaft has a worm 11 that cooperates with a worm wheel 12 secured to the shaft 13 so that when the motor is running it will rotate shaft 13, which is rotatably mounted in 110 bearings 14 and is provided at its upper end with a bevel gear 15 that meshes with a cor-

responding gear 16 on the end of the shaft 17 (Fig. 6). To the outer end of shaft 17 the arm 6 is connected. This arm carries at its ends red lights 18 which are connected 5 in parallel to the contact segments 19 that are connected to but insulated from the shaft 17. As the shaft 17 rotates the segments 19 alternately come into contact with brushes 20 and 21 which are electrically connected to 10 the batteries when the signal is made operative by the closure of the float-operated switch or the thermal circuit closure, which will be hereinafter described. Supported on cement piers 22 is a tower which is preferably formed from corner angles 23 connected by diagonal braces 24. The upper ends of angles 23 are connected by a platform 25 which support a plurality of U-shaped bars 26 which serve as a support for 15 the float 27 which may be formed from galvanized iron or sheet copper. A rod 28 is secured to the upper end of the float and projects through an opening in platform 25. Secured to the upper side of the platform is 20 an enclosing housing 29 carrying two spaced, insulated terminals 30 and 31. A flexible conducting member 32 is secured to terminal 31 and spaced from, but adapted to be moved into contact with the terminal 30. 25 Whenever the water level of the stream rises above the lower end of the float 27, it will raise the latter and cause the upper end of rod 28 to engage the flexible member 32 and move the same against contact 30 so as to 30 electrically connect terminals 30 and 31 which are connected to wires 33 and 34. Secured at spaced intervals to the ties 35 are 35 thermal circuit closers 36, the construction of which is shown in Fig. 3, and which consist of a cap member 37 that is secured to the underside of the ties by means of screws 38. A circular plate of insulating material 39 has secured to the underside thereof a number of spring terminals 40 whose lower 40 ends approach, but do not touch. Secured to the underside of the plate 39 by means of wax or easily fusible solder is a metal ball 41. Wires 42 and 43 each connect one terminal 40 to the circuit composed of wires 45 33 and 34. If the bridge catches fire, the heat will melt the wax or the solder which supports the ball 41 and the latter will drop into the dotted line position shown in Fig. 5 where it will connect the terminals 40 so 50 that current may flow between wires 33 and 34. The terminals 40 are enclosed by a cover 44 and secured to cap 37 by means of screws 45. Referring now more particularly to Fig. 5, it will be noted that wire 33 extends to 55 one terminal of the battery 9 and is also connected to the switch terminal 46, while wire 34 connects terminal 30 and one terminal of each of the thermal circuit closers 36 with the switch terminal 47. A wire 48 extends 60 to the other terminal of the battery 9 to

the motor terminal 49, from the other terminal 50 of which a wire 51 extends to the central switch contact 52. The signals 3, 4 and 5 are connected in parallel relation with the motor terminals 49 and 50 so as to be 70 subjected to the counter-electromotive force of the motor. A switch blade 53 is pivoted intermediate its ends at 54 to the central switch contact 52. Switch blade 53 is angular so that it will make connections between 75 the central contact 52 and either one of the contacts 46 or 47. A spring 55 holds the switch blade normally in contact with contact 47. To the switch blade 53 I secure an insulating member 56 which serves as a handle for moving the switch blade from one position to the other. For the purpose of throwing the switch from the position shown to a position in which connection is made between contact 52 and 46, I have provided the 80 following means:

Secured to the motor shaft 57 is a cylindrical member 58. This member is held in place on the shaft by means which prevents relative rotation thereon. Secured to the 90 base upon which the motor and the switch are mounted is a bracket 59 which has a square opening near its top for the reception of the square portion 60 of a reciprocable member whose other end is provided with 95 square threads 61 and projects into the cylindrical member 58, which has a pin 62 extending through the side thereof and into one of the threads. Near the inner end of the threaded member there is an annular 100 groove 63.

If the motor rotates in the direction of the arrow 64, it is evident that the reciprocable member will be moved to the right owing to the interaction of the pin 62 with the 105 threads 61. When the pin reaches the groove 63, it can rotate freely without causing further movement of the threaded member. Between the square portion 60 and the threaded portion 63 there is an enlarged 110 portion 65 having a shoulder 66 which engages the upper end of the lever 56 and rotates the switch blade 53 about its pivot 54 in a clockwise direction until it makes contact with the switch contact 46 and 115 contacts contact with the contact 47.

Let us now consider a case in which the several parts are in the position shown in Fig. 5 and let us suppose that the float 27 is moved upwardly so as to close the connection between 30 and 32. Current will then flow from the battery 9 through wires 33 and 34 to switch contact 47, thence through switch blade 53 to the central switch contact 52, through wire 51 to motor terminal 50 and from the motor terminal 49 to the battery 9 by way of conductor 48. The motor will now rotate in the direction of the arrow 64 and this will move the enlarged portion 65 to the right and throw 120 125 130

the switch into the position in which blade 53 connects 52 with 46. The wire 34 is now eliminated from the circuit so that the operation of the signal will not be interfered 5 with by anything that can happen to the wires that are connected to the bridge. Since the lamps in the signal posts are connected across the motor, they will continue to glow as long as the motor runs. Arm 6 10 will be rotated by the action of the motor and the lamps carried by it will be alternately illuminated and darkened as the brushes 20 and 21 move into and out of contact with segments 19 (Fig. 6). The 15 signals will remain operative until they are stopped, which can only be done by opening the casing 7 and cutting off the current supply to the motor, after which the motor is rotated in the reverse direction until the 20 switch assumes the position shown in Fig. 5.

In order that the signal shall be audible, as well as visible, I have provided post 3 with a gong '68 that will be sounded whenever the signal operates.

25 My thermal circuit closer can be used in connection with fire alarm systems for schools, residences and other buildings, as well as bridges.

From the above, it will be evident that I 30 have produced a signal means that can be readily applied to bridges and which will become operative whenever the water in the stream rises above what is considered to be a safe level or if the bridge catches afire. 35 The signal is so constructed that after it has once been made operative it will continue to be operative regardless of what happens to the bridge.

Having now described my invention, 40 what I claim as new is:

1. A safety signal system for railway bridges comprising, in combination, a bridge, a railway track, a signal post located by the side of the track at some distance from the bridge, a float-operated switch, means for closing said switch when the water under the bridge rises above a predetermined level, and means comprising said switch for rendering the signal operative when the float-operated switch has closed, said means being independent of said switch after it has been made operative.

2. A safety signal system for railway bridges comprising, in combination, a bridge, a railway track, a signal post located by the side of the track at some distance from the bridge, an open electric circuit, means comprising a switch for closing said circuit when the water rises above a predetermined level, means for closing said circuit in case the bridge catches fire, means

for rendering the signal operative when the circuit has been closed and means for disconnecting said switch and said second means when the circuit has been closed. 65

3. A safety signal system for railway bridges comprising, in combination, a bridge, a railway track, a plurality of signal posts located at spaced intervals along the track, a signal lamp attached to each post, an open electric circuit extending along said bridge, means for closing said circuit when the water exceeds a predetermined level, means for closing the circuit when the bridge burns, means for rendering the signal lamps operative when the circuit extending to the bridge is closed and means for disconnecting said normally open circuit after the signal has been operated. 75

4. A safety signal system for railway bridges comprising, in combination, a bridge, a railway track, a plurality of signal posts located at spaced intervals along the track, a signal lamp attached to each post, means associated with one post for rotating the signal lamp, said means comprising a motor, a source of electric energy, an open electric circuit extending along said bridge, means comprising a float-operated switch for closing said circuit when the water rises above a certain level, means for closing said switch when the bridge catches fire, means for rendering the signals operative when the circuit is closed, and means for automatically disconnecting said portion 85 of the circuit extending to the bridge when the signals have been rendered operative. 90

5. In a railway bridge signal system, in combination, a bridge, a railway track, a plurality of signal posts located along the side of the track on each side of the bridge, one of said signal posts carrying an arm rotatably mounted thereon, a signal lamp in each end of said arm, means for causing said arm to rotate, a source of electrical energy, means comprising electrical conductors for connecting the lamps to the source of power, means for alternately making and breaking the circuit to the lamps while they are rotated, an open electric circuit extending from the source of electrical power to the bridge, means for closing said circuit when the water exceeds a predetermined level, said means comprising a float-operated switch, means for closing said circuit in case the bridge burns, said means comprising a thermal circuit closer, and means for disconnecting said portion of the circuit extending to the bridge after the signals have started to operate. 100 110 115 120

In testimony whereof I affix my signature.
JOHN S. BAY.
